(57) **CLAIM**

I claim the ornamental design for a toilet paper dispenser, as shown and described.

DESCRIPTION

FIG. 1 is a front view of a toilet paper dispenser;
FIG. 2 is a back view of a toilet paper dispenser;
FIG. 3 is a top view of a toilet paper dispenser;
FIG. 4 is a bottom view of a toilet paper dispenser;
FIG. 5 is a left view of a toilet paper dispenser;
FIG. 6 is a right view of a toilet paper dispenser; and,
FIG. 7 is an isometric view of a toilet paper dispenser.
The broken lines show portions of the design that form no part of the claimed design.
